UNITED STATES PATENT OFFICE

2,190,096

WINDOW FRAME

Harry W. Cook, Malta, Ohio

Original application May 2, 1938, Serial No. 205,852. Divided and this application December 30, 1938, Serial No. 248,540

3 Claims. (Cl. 20—12)

This invention relates to the construction of window frames or the like and more particularly to an improvement of the inside trim over the weight box of a sliding member such as window sash.

The object of the invention is to provide a construction in which said trim can be easily and quickly applied and removed, the latter for the purpose of uncovering the weight box and thereby afford access to the weight and its cord in the event they need attention.

Further objects will appear from the disclosure herein.

The invention is embodied in the preferred example herein shown and described, the feature of novelty being finally pointed out in the claims.

In the accompanying drawing—

Figure 1 is a view in elevation from the inner or room side of the right hand portion of a window frame, a sash with cord and weight with parts broken out and in section and according to the invention.

Fig. 2 is a vertical section broken out horizontally showing the right hand side of the window frame alone, that is without illustrating any moving parts installed therein.

Fig. 3 is a horizontal section on the line III—III Fig. 2 looking down.

Fig. 4 is a detail of the right hand portion of Fig. 3 on a larger scale.

In the views the character 20 designates the sill, and 21 the vertical face trim. The character 22 designates the inside stop, and 23 an inside strip.

The inside strip 23 which is secured to the inner edge of the pulley stile 9 by screws said strip having a longitudinal groove or plough 23^a that is engaged by the hook end of screw hooks 24 threaded into the face trim 21, said hooks each adapted to have its hook end turned into said groove to hold said face trim 21 in position at one edge.

The face trim 21 is provided at its inner edge with a tongue 21^a, and a shoulder 21^b, said tongue engaging a groove 22^a in the stop 22 while the shoulder 21^b engages the inside strip 23.

The upper end of the face trim 21 is mitred to slip under a corresponding mitre of the head strip 18 so that when one or more screws as at

19 are applied to connect the inside stop with the pulley stile, or to the inside strip 23 thereon, the face trim 21 and stop 22 are held together without other fastening and subject to easy separation at any time to permit access to the weight box. By loosening the screws 19 and turning out the hooks 24, the face trim can be alone removed.

The strip 23 in the form shown can be used at the opposite side of the window frame and for that reason is called a reversible strip.

In Fig. 1 there is shown at 9 the pulley stile, a sash 17, a sash weight 14^a and the usual cord 16^b for connecting the weight and sash said cord traveling around a pulley wheel at the top of 15 the frame, said pulley wheel not being shown but its frame 11 only.

The forms of the parts can be changed without departing from the gist of the invention as claimed.

The application for this patent is a division of an application filed by me May 2, 1938, S. No. 205,852.

What I claim is:

1. In a window frame or the like having a pulley stile and a weight box, a readily removable inside sash stop, an inside strip secured to the pulley stile and extending into the weight box, a weight box cover or casing strip removably engaged at one edge with said sash stop and provided near its other edge with a readily removable hook member for engaging said inside strip.

2. In a window frame or the like having a pulley stile and a weight box, an inside sash stop, an inside strip having a longitudinal groove secured to the pulley stile and extending into the weight box, a weight box cover or casing member engaged at one edge with said sash stop and having near its other edge a readily movable member thereon to engage the longitudinal groove of the aforesaid inside strip.

3. In a window frame or the like having a pulley stile and a weight box, an inside sash stop, an inside strip secured to the pulley stile and extending into the weight box, a weight box cover or casing member engaged at one edge with said sash stop and having near its other edge readily removable means for engaging said inside strip.

HARRY W. COOK.
